LIFTING TRUCK

Jakob Loef, Moosburg, Germany

Application June 29, 1932, Serial No. 620,002
In Germany December 23, 1931

25 Claims. (Cl. 254—2)

This invention relates to lifting trucks, and more especially to lifting trucks of the type utilizing a steering and lifting lever adapted to impart elevating movement to a lifting platform.

5 This invention relates more especially to the construction of a hand lift truck in which the lifting mechanism may be readily adapted for operation by hydraulic means step by step jack means or other lifting devices now well known in 10 the art.

In the main, the invention embodies the arrangement of a truck having an elevating platform carrying a lifting link member adapted to extend into the steering axis and to be operated 15 by a lifting member movable in the steering axis and actuated in turn by a lifting lever which is preferably the steering lever. In this form of mechanism it is required that the lifting portion of the elevating link member be maintained in the steering axis by some type of guide means. Since 20 I generally prefer to utilize a lifting member which is loosely pivoted to the lifting lever and which is guided solely by its engagement with the link member carried by the elevating platform, I 25 arrange for guide means associated with the elevating link member for maintaining its lifting portion in the steering axis during the lifting operation. There are a number of other features 30 of my invention and its modifications which I will describe hereinafter and which are valuable contributions to the art.

For a description of my invention and the modifications thereof, I shall now refer to the drawings wherein Fig. 1 is a partial sectional view of 35 the front end of a truck illustrating the operation of the lifting means. Fig. 2 is a view of parts of Fig. 1 showing the mechanism in a position corresponding to an elevated position of the platform. Fig. 3 is a front view of parts of the truck, 40 whereas Fig. 4 is a plan view of the parts of Fig. 3. Figs. 5, 6, and 7 are respectively a side, front and plan view of a modification of my invention in which the lifting is done by a U-frame. The right hand portions of Figs. 6 and 7, and parts of Fig. 5 45 illustrate a modification in which no check is utilized and wherein the handle controls the downward movement of the elevating platform. Figs. 8 and 9 show a modification of my invention in which the elevated platform is shown respectively in a lowered and a lifted position. Figs. 10 and 11 show a further modification of my invention. Fig. 12 shows a still further modification. Figs. 13 and 14 show a modification of my truck 50 utilizing a mechanical jacking movement. Figs.

15 and 16 show a modification utilizing a hydraulic jacking movement.

Referring now to the drawings, and especially Figs. 1 and 2, my truck comprises an elevating frame 2 pivotally supported by means of links 3 5 relatively to a main frame 1, the links 3 being pivoted to the elevating frame as at 7 and to the main frame as at 8. The front wheels 4 are mounted on the axle 5 which in turn is journaled on a spindle member 17 which is supported in the frame 16 by means of pins 18. The frame 16 in turn revolves about the axis of spindle 13 through the intermediary of a bushing 9 surrounding said spindle and conical roller bearings 12. The main frame comprises a cross-head 6 having a thrust bearing relationship with the frame 16 through the intermediary of ball bearings 11. The bushing 9 continues upwardly and terminates in a steering head 10 which is adapted to support the lifting lever 23.

The lifting lever 23 is mounted on pivot 21 carried by the member 10, and is limited in its movement relatively to the member 10 by a stop 24 cooperating with a stop 25 on the member 10. In order to counterbalance the lifting lever 23, there is utilized a spring 22 secured to the lifting lever at one end and at the other end to a lever 20 which, in turn, is secured by a connecting rod 19 to the spindle 13. It will be readily appreciated that downward movement of the lifting lever 23 20 from its position of Fig. 1 to Fig. 2 will be resisted by the spring 22. This is an especially important function of my invention because it prevents the accidental dropping of the lever 23 when accidentally released and avoids the injuring of persons that might otherwise be in its path of movement.

The lifting lever 23 has an extension to which the lifting strut member 27 is pivoted at 26. The member 27 is movable into various positions by a foot pedal 28 integral therewith. With the lifting lever 23 in its position of Fig. 1, the member 27 30 may occupy the dotted line position in which its plane surface 29 abuts a corresponding surface 32 on the cross-head 6. In this position of the parts, best illustrated in Figs. 1 and 4, the lever 23, together with the member 10 to which it is pivoted and which constitutes an extension of the rotatable sleeve 9, will be held against rotation relatively to the head 6, due to the fact that abutting 35 surfaces 29 and 32 will hold member 27 and consequently the lever 23 in a straight ahead position. At the same time, the lever will be held against pivotal movement in a counter-clockwise direction about its pivot 21. It will, therefore, be 40 45 50 55

able to serve as a pushing member for the truck, the steering being accomplished by the caster relation of the wheels 4 to the head 6. In the full line position of the member 27, it is merely maintained out of obstructing relation relatively to the head 6 so that the lifting lever 23 may be manipulated with facility.

The lifting member 27 is equipped at its upper end with a relatively conical surface 30 which, 10 in turn, cooperates with a corresponding socket in the member 36. Member 36 is, in turn, supported on pin 35, carried by the ear members 34 forming an extension of the lifting link 33. Because of the shape of the pin 35, the part 36 has 15 a relatively universal movement, within limitations. The link member 33 is supported on pivots 48 at either side of the elevating platform and is adapted to pivot relatively to the platform. It is understood that when lifting effort is applied to 20 the link member 33 as by the lifting member 27, there will be a natural tendency to separate the surfaces of the member 27 and the member 36 so as to cause a rearward swinging of the link 33. Even if means were present to prevent this rear- 25 ward swinging of the link 33, it would still be necessary to provide means for maintaining the link 33 in such a position that the member 36 might constantly be in the steering axis of the truck in order that side lift movement by the 30 handle 23 might be possible. This is especially required where lever 23 functions as a steering lever through fixed relationship between steering head 6 and the wheels 4. For this purpose I, therefore, provide guide links 37 which are pivoted 35 at 47 to each side of the link member 33 and at 40 to each side of the cross-head 6. These guide links 37 are of such length and shape and are so positioned that they guide the link member 33 and maintain its portion 36 substantially in alignment with the steering axis of the truck during 45 the entire lifting operation of the lever 23.

It is thought that the operation of the lifting mechanism so far described will be quite apparent, but it will be best to indicate the general 45 operation before going further with the explanation of the remaining parts of my invention. The lever 23 is held in an upward initial position, and the foot treadle 28 is operated to bring the member 27 into cooperation with the socket of the member 36. Thereafter, a downward movement 50 of the lever 23 brings the parts into the position of Fig. 2 with the lever 23 firmly against the stop 25 of the member 10. During this movement, the link 33 has been maintained in proper relation to the lifting member 27 by the links 37. Also, the movement of the lifting member 23 has 55 been resisted by the spring 22 through its connection with the spindle member 13. When the parts reach a fully lifted position, a foot lever 41, pivoted at 40 or on the same axis as one of the 60 levers 37, and which has a hook-shaped end 63, catches the bushing 42 carried on pin 48 for maintaining the elevated platform in its fully elevated position.

65 It will be understood that between frames 1 and 2, there will preferably be positioned a lowering brake so as to slow down the lowering movement of the elevating platform 2 when it is released by the foot pedal 41. It will be further 70 understood that once the parts are lifted as shown in Fig. 2, return movement of the member 23 will relieve the tension between the surface 30 of the lifting member 27 and the socket of the member 36, so that the member 27 will tend to fall out of 75 cooperative relation to the member 36. In case

the elevating platform is released for downward movement, this release will prevent the hitting of the member 36 against the lifting member 27, thus preventing a flying upwards of the handle 23, termed in the trade "a flying handle hazard." 5

Figs. 10 and 11 show a modification of my invention in which the link member 33 carries a strut member 71 mounted about the pin 35 in a manner similar to the member 36 of Figs. 1 and 2, so as to have a pivoting movement in two planes. 10 This strut is adapted to be actuated by a pin 72 mounted in the bearings 50 formed on an extension of the operating lifting lever 23. When the elevating platform has been lifted, the pin member 72 moves to its dotted line relation to 15 hooks 73 illustrated in Fig. 10 by rolling down through gravitational action into locked relationship with said hook members 73. It can only be released from its relation to hook members 73 by 20 operation of the treadle 74, as will be readily apparent. Once it is released, the pin 72 will drop downward into its initial full line position shown in Fig. 10 wherein it will again be in position to operate strut 71 to elevate the platform.

In a construction such as that shown in Figs. 25 10 and 11, the movement of the lifting lever may be obstructed by the cam 76 integrally related to the lever 77 pivoted at 78. This lever 77 has an extension 68 which fits into a slot 79 provided in the cross-head 6 and naturally locks the steering 30 lever 23 and, therefore, the rotatable sleeve 9, against rotary movement relatively to the cross-head 6. This relation of the parts also locks the lever 23 against downward lifting movement and makes it possible to handle the truck in the manner of a caster truck by merely pushing and pulling on the handle 23 as it is in its upright position. It will be quite simple to release the lever 23 from this position by merely stepping on the treadle 70 of the lever 77, thus moving the cam 40 portion 76 out of obstructing relation to the surface 69 of the lever 23.

In Figs. 8, 9, and 12, I illustrate further modifications of my invention in which the operating lifting elements are substantially the same as 45 those of Figs. 1 and 2, except that I substitute for the pivoting lever 33 used in Figs. 1 and 2 the fixed member 82 projecting from the front end of the elevating platform 2 and adapted to move integrally therewith. In a modification of this 50 sort, it is naturally not necessary to provide guide means for the lifting member 82 as required for the link 33 of Figs. 1 and 2, since the lifting member 82 is integral with the platform and can only move therewith. Therefore, in order to insure 55 that the socket of the member 36 in Figs. 8 and 9 will move substantially in the steering axis of the truck so as to be operated by the lifting member 27 which, in turn, is actuated by lever 23, means must be provided to move the elevating 60 platform in a substantially vertical direction. At the same time, the lifting arrangement must be such as to make it possible to operate the lifting mechanism by the member 27 movable in the steering axis.

In order to solve this problem, which is quite considerable. I have devised a lifting connection between the main and elevating frames which will readily contribute the results desired. I utilize a lever 84, of which there will be one on each side of the truck, having a pivot 79 mounted for sliding movement within the bearing 80, it being equipped with a roller 86 to permit this movement. Secured to each link member 84 by means of pivot 81 is a lever member 85, in turn 75

pivoted at point 8 on the main frame. The end of each link 84 opposite the pin 79 is, in turn, pivoted at point 7 to the elevating frame 2. The distances 19—81, 81—7, 81—8 are all equal and 5 comprise the Evans swinging link guide system. This relationship of the parts makes it possible for the elevating platform 2 to move in a substantially vertical direction when actuated by the member 21, this movement being well illustrated 10 in Figs. 8 and 9. In this way I obtain a vertical movement also of the member 82 so that its lifting portion 36 remains always in the steering axis for operation by the lifting member 27 of lever 23.

Figs. 13, 14, 15, and 16 show modifications of 15 my truck in which the single lift mechanism may be adapted for multiple lifting in which a plurality of reciprocations of the lifting lever 23 are required. In this modification a more simple type of front bearing for the wheels 4 has been 20 shown in order to simplify the explanation of the more important features of the invention. The sleeve 9 is equipped with a bore in which the journal 91 of the hydraulic pump shown in Fig. 15 is guided. This pump has a piston 93 equipped 25 with a pivotal bearing 92 by means of which it may be secured to the eye members 34 of the link 33 through pin 45. This pin 45 in turn operates 30 in slots 92a of eyes 34 of the strut member 33. In this way, it may contribute lifting movement to the elevating platform. The hydraulic jack piston 93 has a stuffing collar 94 and is adapted to slide in the cylinder 98. As illustrated, the cylinder 98 is surrounded by a hollow space, the latter being defined by another cylinder 99, both cylinders being held in position at their tops as well as at their bottoms by means of end piece 97 provided with stuffing boxes 96. On one side of the cylinder 99, the pump 103 is secured and is arranged to be actuated by the link 102, in turn 40 operated by lever 104. This hydraulic jack will operate in the usual manner well known in the art, the liquid being drawn out of the space from between the cylinders 98 and 99, and forced by the pump 103 through the hole 100 against the 45 lower side of the piston 93 whereby the latter will be moved upwardly and will actuate the lifting link 33. The cylinder 98 is provided with an exhaust hole 101 which is adapted to permit a lowering of the piston 93 as the exhaust hole is 50 opened by means of a screw or other type of mechanism. In this way, the hydraulic pump itself may be substituted also for the usual hydraulic jack utilized in trucks of this type.

While the pump has been shown as actuated 55 by the lever 104, actually the lever may be operated by the lifting lever 23, if connected thereto as by a collar similar to collar 116 in Fig. 13.

In Figs. 13 and 14, I illustrate just how the hydraulic jack means of Figs. 15 and 16 may be dispensed with and a mechanical jack utilized. This jack, as shown in Figs. 13 and 14, comprises a vertical spindle member 110 secured to the eye members 34 by pin 45, and may be actuated in a lifting direction by cam 115 which, in turn, 60 is operated by the lever 104 pivoted at 114. This operation of the cam is transmitted to the spindle member 110 through an angularly arranged friction wedge ring 111, which in its position of Fig. 14 is wedged to spindle 110. Lever 104 moves 65 spindle 110 through ring 111 when the lever is swung downwardly. Wedge ring 112 is fixed at 112a to housing 113 and while it allows upward movement of spindle 110, it will prevent downward movement of said shaft. To obtain 70 a lowering of the spindle, upward pressure must 75

be applied by a tool to the left end of the wedge 112, looking at Fig. 14, thus releasing the spindle.

It will be readily understood that the utilization of such mechanisms as shown in Figs. 13-16 inclusive, is also entirely dependent upon the 5 maintenance of the upper lifting portion of the link 33 in the steering axis, this being, in turn, made possible by the guiding of the link 33 through means of the levers 37.

It is sometimes desirable to operate trucks by 10 U-handles instead of by the ordinary lifting lever. A modification of this type is shown in Figs. 5, 6 and 7. In this modification, ear member 34 carried by link member 33 is equipped with a slot 66 in which may operate the pin extension of a 15 modified form of member 27. The member 27, in turn, is mounted on a cross-piece 51 extending across the front end of the truck and pivoted on pins 56 to ear members 57 provided on the main cross-head 6. The extensions 58 of a U-handle fit 20 in sockets 52 and will operate the cross member 51 and the lifting member 27 similarly to its manner of operation by a single lever 23. While I have illustrated the member 27 as operating in slot 66 of the lifting extension of the link 33, 25 the member 27 may in reality be exactly similar to member 27 illustrated in Figs. 1 and 2. I illustrated the particular construction only because I utilize it with my checkless truck modification shown in Figs. 5, 6, and 7. 30

It sometimes becomes desirable to manufacture a truck such as that described in Figs. 5, 6 and 7 without a checking member. In a construction of this type, it is necessary to control the lowering of the load by the same means that do the 35 lifting, in this case the U-handle 58. It is also necessary to prevent the lowering of the load until the U-handle has been placed in a position for controlling the lowering. Because of this last necessary feature, my hook 63 which does the 40 locking of the elevating platform in an elevated position is equipped with a hook 64 adapted to be actuated by a nut 62 on the end of the trigger 59 movable integrally with the U-lifting member 58. It is impossible to release the elevating platform by moving the hook 63 out of coaction with the sleeve 48, except through the nut extension 62 of the trigger 59. The nut 62 does not fit within the hook 64, except when the handle 58 45 is in a fully downward position in which position 50 the member 59 may be moved against the opposition of spring 60 to perform the releasing operation. It will be naturally understood that releasing of the elevating platform is impossible, therefore, except when the U-handle 58 is in position 55 to control the lowering of the platform 2. 55

While I have shown several modifications of my invention, it should be understood that additional variations will readily occur to those skilled in the art. 60

I claim:

1. In a lift truck, a main frame having a steering head, an elevating frame movable forwardly and upwardly relatively to said main frame, a link member pivoted to said elevating frame and having a portion thereof extending over into the axis of the steering head so as to be operated by a lifting member movable substantially vertically in the said axis, and a guide member pivotally associated with said main frame and with said link member for guiding said link member to maintain its lifting portion substantially in the steering axis as said elevating frame moves forwardly and upwardly. 65

2. In a lift truck, a main frame having a steer- 70

75

ing head, an elevating frame movable forwardly and upwardly relatively to said main frame, a link member pivoted to said elevating frame and having a portion thereof extending over into the axis of the steering head, a lifting lever, a lifting member pivoted thereto and movable substantially vertically in the steering axis when guided therein and adapted to engage said link member portion to impart an elevating movement 5 to said elevating frame upon downward movement of the steering lever, said lifting member being guided for movement in the steering axis by said lifting link portion, and a guide member pivotally associated with said main frame and 10 with said link member for guiding said link member to maintain its lifting portion substantially in the steering axis as said elevating frame moves forwardly and upwardly.

3. In a lift truck, a main frame having a steering head, an elevating frame movable upwardly relatively to said main frame, a link member secured to said elevating frame and having a portion thereof extending over into the axis of the steering head, a lifting lever, a lifting member pivoted thereon and normally adapted to lie in a forward or rearward position so as not to interfere with the movement of said lifting lever, said member being movable substantially vertically in the steering axis when guided there- 20 in and adapted to impart lifting effort to said link member to elevate the elevating frame upon downward movement of the lifting lever, said lifting member being guided for movement in the steering axis by its engagement with said 25 lifting link portion, and means whereby said lifting link portion is maintained substantially in the steering axis in all the positions of the elevating frame.

4. In a lift truck, a main frame having a steering head, an elevating frame movable forwardly and upwardly relatively to said main frame, a link member pivoted to said elevating frame and having a portion thereof extending over into the axis of the steering head, a lifting lever, a lifting member pivoted thereon and normally adapted to lie in a forward or rearward position so as not to interfere with the movement of said lifting lever, said member being movable substantially vertically in the steering axis when guided 40 therein and adapted to impart lifting effort to said link member to elevate the elevating frame upon downward movement of the lifting lever, said lifting member being guided for movement in the steering axis by its engagement with said 45 lifting link portion, and guide means for said link adapted to guide it so as to maintain its lifting portion substantially in the steering axis as said elevating frame moves forwardly and upwardly.

5. In a lift truck, a main frame having a steering head, an elevating frame movable forwardly and upwardly relatively to said main frame, a link member pivoted to said elevating frame and having a portion thereof extending over into the axis of the steering head, a lifting lever, a lifting member pivoted thereon and normally adapted to lie in a forward or rearward position so as not to interfere with the movement of said lifting lever, said member being movable substantially vertically in the steering axis when guided there- 60 in and adapted to impart lifting effort to said link member to elevate the elevating frame upon downward movement of the lifting lever, said lifting member being guided for movement in the steering axis by its engagement with said 65 lifting link portion, and a guide member pivotally associated with said main frame and with said link member for guiding said link member to maintain its lifting portion substantially in the steering axis as said elevating frame moves forwardly and upwardly.

6. In a lift truck, a main frame having a steering head, an elevating frame movable forwardly and upwardly relatively to said main frame, a link member pivoted to said elevating frame and having a free-end portion thereof extending over 10 into the axis of the steering head so as to be engaged and operated by a lifting member movable substantially vertically in the said axis, and guide means for said link independent of said lifting member and adapted to guide said link and move 15 it on its pivot relatively to said elevating frame so as to maintain its free end lifting portion in the steering axis as said elevating frame moves forwardly and upwardly.

7. In the combination of claim 1, a foot lever 20 associated with said lifting member for moving it into the steering axis for engagement with said link portion.

8. In the combination of claim 1, the engagement between said link portion and said lifting 25 member being in the form of a ball and socket connection.

9. In the combination of claim 2, said lifting member being adapted to drop from engagement with said link portion and out of obstructing relation to said lifting lever upon the relieving of 30 the lifting tension between said member and said lifting portion.

10. In the combination of claim 3, said lifting member being adapted to drop from engagement 35 with said link portion and out of obstructing relation to said lifting lever upon the relieving of the lifting tension between said member and said lifting portion.

11. In a truck, a steering and lifting lever, a 40 cross-head relatively to which said lever is rotatable for steering action, and relatively to which it is so pivoted for lifting action, a shoulder portion associated with said steering lever and a second shoulder portion associated with said head 45 adapted to be engaged when said lifting lever is placed in a vertical position, said shoulder portions being cooperable to prevent both rotary movement and rearward pivoting movement of said lever.

12. In a truck, a steering and lifting lever, a cross-head relatively to which said lever is rotatable for steering action, and relatively to which it is pivoted for lifting action, a lifting member pivoted to said lever and adapted to drop into a backward position out of obstructing relation to said lever, and also into a downward position, a shoulder portion on said member, and a shoulder portion on said cross-head against which said member shoulder portion is arranged 55 to abut when moved into said downward position, said shoulder portions being cooperable to prevent both rotary movement and rearward pivoting movement of said lever.

13. In a truck, a steering and lifting lever, a cross-head relatively to which said lever is rotatable for steering action, and relatively to which it is so pivoted for lifting action, a lifting member pivoted to said lever and movable into a downward position when said lever occupies a vertical position, a shoulder portion on said member, and a shoulder portion on said cross-head against which said member shoulder portion is arranged to abut when moved into said 70 downward position, said shoulder portions being 75

cooperable to prevent both rotary movement and rearward pivoting movement of said lever.

14. In a lifting truck, a main frame, an elevating frame, links connecting said main and elevating frames and adapted to lift said elevating frame relatively to said main frame, and guide links pivoted to said main frame and to said connecting links for so guiding the connecting links that the movement of said platform will be substantially vertical.

15. In a lifting truck, a main frame, an elevating frame, links connecting said main and elevating frames and adapted to lift said elevating frame relatively to said main frame, said links being slideable relatively to one of said frames, and guide links pivoted to said main frame and to said connecting links and adapted to control said links and their sliding movement so that the movement of said platform will be substantially vertical.

16. In a lifting truck, a main frame, an elevating frame, links connecting said main and elevating frames and adapted to lift said elevating frame relatively to said main frame, said links being slideable relatively to one of said frames, and guide links pivoted to one of said frames and to said connecting links and adapted to control said links and their sliding movement so that the movement of said platform will be substantially vertical.

17. In a lift truck, a main frame having a steering head, an elevating frame mounted for upward movement relatively to said main frame, a lifting unit secured to said elevating frame and having a portion overlying the steering head axis, a lifting member movable substantially in the steering axis for operating said lifting unit, and means independent of said lifting member for guiding said lifting unit during lifting movement thereof and during operation of said lifting member whereby to maintain said lifting unit portion substantially in the steering head axis for continuous effective operation by said lifting member.

45 18. In a lift truck, a main frame having a steering head, an elevating frame mounted for upward movement relatively to said main frame, a lifting unit secured to said elevating frame and having a portion overlying the steering head axis, a lifting member movable substantially in the steering axis for operating said lifting unit, and rigid link guide means independent of said lifting member for guiding said lifting unit during lifting movement thereof and during operation 55 of said lifting member whereby to maintain said lifting unit portion substantially in the steering head axis for continuous effective operation by said lifting member.

60 19. In a lift truck, a main frame having a steering head, an elevating frame movable upwardly relatively to said main frame, a lifting unit secured to said elevating frame and having a portion thereof extending over into the axis of the steering head, a lifting lever, a lifting member pivoted thereon and normally adapted to lie in a forward or rearward position so as not to interfere with the movement of said lifting lever, said member being movable substantially vertically in the steering axis when guided therein and 65 adapted to impart lifting effort to said lifting unit to elevate the elevating frame upon downward movement of the lifting lever, said lifting member being guided for movement in the steering axis by its engagement with said lifting unit portion, and means whereby said lifting unit is

70 maintained in the axis of the steering head during the lifting of said elevating frame.

20. In a lift truck, a main frame having a steering head, an elevating frame mounted for upward movement relatively to said main frame, a lifting unit secured to said elevating frame and having a portion overlying the steering head axis, a lifting member movable substantially in the steering axis for operating said lifting unit, means mounting said lifting member whereby the contact of 10 said overlying portion of the lifting unit with said lifting member maintains said member in the steering head axis, and means for guiding said lifting unit during lifting movement thereof and during operation of said lifting member whereby 15 to maintain said lifting unit portion substantially in the steering head axis for continuous effective operation by said lifting member.

21. In a lift truck, a main frame having a steering head, an elevating frame mounted for 20 upward movement relatively to said main frame, a lifting unit secured to said elevating frame and having a portion overlying the steering head axis, a lifting lever pivoted to said steering head, a lifting strut member pivoted at its lower end to said 25 lever and movable into substantial alignment with the steering axis and with its upper end in thrust contact with the overlying portion of the lifting unit, whereby downward swinging movement of the lifting lever will elevate said elevating frame, said lifting strut member being movable automatically out of engagement with said lifting unit overlying portion when its thrust contact with said overlying portion is relieved, and means for guiding said lifting unit, and incidentally said strut member, substantially in the 30 steering axis during the lifting operation.

35 22. In a lifting truck, a main frame having a steering head, an elevating frame, links connecting said main and elevating frames and adapted 40 to lift said elevating frame relatively to said main frame, guide links pivoted to said main frame and to said connecting links for so guiding the connecting links that the movement of said platform will be substantially vertical, a lifting unit 45 secured to said elevating frame and having a portion extending into the steering head axis, and a lifting member movable substantially in the steering head axis for operating said lifting unit.

23. In a lifting truck, a main frame having a 50 steering head, an elevating frame, links connecting said main and elevating frames and adapted to lift said elevating frame relatively to said main frame, said links being slideable relatively to one of said frames, guide links pivoted to said main 55 frame and to said connecting links and adapted to control said links and their sliding movement so that the movement of said platform will be substantially vertical, a lifting unit secured to said elevating frame and having a portion extending 60 into the steering head axis, and a lifting member movable substantially in the steering head axis for operating said lifting unit.

24. In a lifting truck, a main frame having a steering head, an elevating frame, links connecting said main and elevating frames and adapted to lift said elevating frame relatively to said main frame, said links being slideable relatively to one of said frames, guide links pivoted to one of said frames and to said connecting links and adapted 70 to control said links and their sliding movement so that the movement of said platform will be substantially vertical, a lifting unit secured to said elevating frame and having a portion extending into the steering head axis, and a lifting 75

member movable substantially in the steering head axis for operating said lifting unit.

25. In a lifting truck, a main frame having a steering head, an elevating frame, links connecting said main and elevating frames and adapted to lift said elevating frame relatively to said main frame, guide links pivoted to said main frame and to said connecting links for so guiding the connecting links that the movement of said platform 10 will be substantially vertical, a lifting unit secured to said elevating frame and having a portion overlying the steering head axis, a lifting lever

pivoted to said steering head, a lifting strut member pivoted at its lower end to said lever and movable into substantial alignment with the steering axis and with its upper end in thrust contact with the overlying portion of the lifting unit, whereby downward swinging movement of the lifting lever will elevate said elevating frame, said lifting strut member being movable automatically out of engagement with said lifting unit overlying portion when its thrust contact with 10 said overlying portion is relieved. 5
